UNITED STATES PATENT OFFICE

WAYNE B. THOMAS, OF YOUNGSTOWN, OHIO, ASSIGNOR TO THE NILES STEEL PRODUCTS COMPANY, OF NILES, OHIO, A CORPORATION OF OHIO

CAP SETTING TOOL

Application filed August 28, 1930. Serial No. 478,537.

This invention relates to improvements in cap setting tools, being intended primarily for attaching and sealing sheet metal caps of cup shaped form to the ends of metal pipes.

One of the objects of the invention is the provision of a tool of this character for quickly and effectively expanding a bead formed in the cap and holding the sealing gasket, whereby the gasket is pressed tightly between the cap and the pipe wall, preventing movement of the cap as well as sealing the joint between same and the pipe.

Another object is the provision of a tool of this kind in which the speed of movement of the operating levers is greatest and the leverage least at the beginning of the work stroke, while the speed is least and the leverage greatest at the end of that stroke, that is, at the time when the load is heaviest.

Still another object is the provision of a tool for the purpose stated in which the moving parts are all protected against injury.

Further objects and features of novelty will appear as I proceed with the description of those embodiments of the invention which, for the purposes of the present application, are illustrated in the accompanying drawings, in which

Figure 1 is a longitudinal sectional view of a pressure fluid tool embodying the invention, the tool being shown in operative relation with a pipe and pipe cap and the operating levers being shown in their inoperative position.

Fig. 2 is a similar view with the operating levers shown at the end of their working stroke.

Fig. 3 is an end view of the tool with the pipe and cap removed.

Fig. 4 is a diagrammatic, longitudinal, sectional view of a valve control means which may be employed in connection with the invention.

Fig. 5 is a transverse sectional view of the same, taken substantially on the line 5—5 of Fig. 4; and

Fig. 6 is a longitudinal, sectional view of a hand operated tool.

The tool herein disclosed is intended pri-

marily for use in connection with the closure or pipe cap described and claimed in the application of David W. Thomas, filed August 6, 1930, Serial No. 478,504. Such caps have particular utility as closures for the ends of heavy gauge steel pipes, as a means for excluding dirt and moisture after the pipes have been cleaned at the factory and until they are laid as parts of gasoline pipe lines, or the like. My invention consists essentially in a means for expanding the cap side wall against an annular gasket, which is thereby compressed between the cap and pipe to constitute an effective seal. This expansion may also bring about a close metal to metal contact on one or both sides of the gasket, thereby assisting the latter in securely holding the cap against accidental dislodgment.

Referring now to the drawings, I have shown at 10 a fragment of one end of a heavy gauge steel pipe having a beveled extremity. The closure cap of cup shaped form is illustrated at 11. It has a flanged rim to fit over the beveled end of the pipe, and is provided with circular beads or corrugations 12 and 13 in the base or bottom portion for strengthening purposes. These corrugations extend downwardly with respect to the inside of the cap in order not to interpose any obstructions to the closing mechanism. The side wall of the cap is provided with an annular inwardly extending bead 14 (see Fig. 1) of semi-circular contour preferably, and in the exterior groove formed by this bead there is mounted an annular soft rubber gasket 15 of circular cross section.

The power tool, illustrated in Figs. 1 to 5 inclusive, may be moved about and held to the work by the operator if desired, but I prefer to mount it in a special frame (not shown). For this purpose the housing 16 may be provided with a series of outwardly projecting eye bolts 17 to receive suitable means for mounting the tool upon the said frame. To the forward end of this housing there is secured a carrier plate or head 18, in the front face of which is formed a circular groove 19 adapted to fit over the flanged extremity of the cap 11 and thereby center the tool with respect to the cap and pipe. Mounted cen-

trally in this plate 18 there is a rearwardly extending post or guide rod 20, at the forward end of which is a portion of reduced diameter which extends through an opening in the plate and is threaded at its extremity to receive a clamping nut 21.

At some distance to the rear of the plate 18 the post 20 is grooved to take a collar 22, which is threaded on its outer side. A piston body member 23 is slipped over this collar and clamped in position by means of two threaded rings or nuts 24 and 25. This body member has an integral offset peripheral portion 26. A separate ring 27 of similar form is removably attached to the body member 23 opposite the part 26. Between these two parts are mounted two oppositely arranged cup leathers 28 and an interposed metal spacer ring 29. The piston of the tool is thus fixed to the post 20.

The cylinder comprises two end members 30 and 31 mounted to slide upon the post 20 and provided with packing glands 32 and 32' to prevent the escape of pressure fluid. A piece of steel tubing 34 constitutes the side wall member of the cylinder, the various parts being held together in proper relation by means of studs 35, which are spaced evenly around the periphery of the cylinder and extend through smooth holes in the end member 31 and are screwed into threaded holes in the end member 30.

On the forward wall of the end member 30 I secure, by means of machine screws 36 or the like, a disc 37, having a central opening of sufficient size to give ready access to the packing gland 32. One or both of the members 30 and 37 has an easy sliding fit within an internally machined portion of the housing 16. Near its periphery the disc 37 carries a series of pairs of forwardly projecting lugs 38, evenly spaced. Each pair carries a pivot 39, and these pivots support the outer ends of links 40. In the drawings these links are shown as formed of two parts 41 and 42 threaded together for the purpose of making the length of the link adjustable, these parts being held in adjustable position by a lock nut 43. The forward ends of the links 40 are pivotally connected with the rear ends or long arms of levers or arms 44 that extend through openings 45 in the plate 18 and are mounted upon tangentially arranged pivots 46 supported in lugs 47 that project forwardly from the plate 18 on either side of each opening 45. Extending laterally outward from the forward ends of each lever 44 there is a presser shoe or jaw 48 which has an outer working face conforming substantially with the inner surface of the cap 11, that is to say its surface is a narrow sector of a cylinder with a diameter approximately the same as the inner diameter of the cap. The shoes

48 are of such length as to bring their ends closely together.

The number of levers and shoes may be varied more or less, a small number having the advantage of simplicity and low cost, and a large number having the advantage of producing more accurate, uniform expansion of the bead. I have found, however, that six shoes, as herein illustrated, give results that are sufficiently good for all practical purposes.

In the two cylinder end members 30 and 31 I form intake and exhaust passages 50 and 51, respectively, which are in communication with the cylinder spaces in front of and behind the piston. Suitable valve control means adapted alternately to direct pressure fluid into these passages and lead the exhaust fluid out of them must be supplied. To this end I may attach metal pipe conductors 52 and 53 to the end members 30 and 31 in communication, respectively, with the passages 50 and 51, and upon these conductors I may support a valve casing 53 within which is mounted a solid cylindrical valve piece 54 that is adapted to be rotated in the casing 53 by means of a handle 55. This valve, of course, travels back and forth with the cylinder 30, 31, 34. Centrally attached to the rear end of the valve casing 53 is a pressure fluid hose or other flexible conductor 56. In the sides of the casing are exhaust ports 57 and 58. In the bottom of the casing are two ports 59 and 60 connected respectively with the pipe conductors 52 and 53. In the valve piece 54 there is an annular passage 61 which is in communication at all times with the flexible supply pipe 56 and may be caused to register with either one of the ports 59 and 60. There are also two curved passages 62 and 63 in the valve piece 54. When the passage 61 is in register with port 60, the passage 62 is in position to connect port 59 with exhaust port 57. Also, when the passage 61 is in communication with port 59, exhaust may take place through port 60, passage 63 and the exhaust port 58. Of course, the pressure in the cylinder on either side of the piston may be held by rotating the valve piece 54 to move passage 61 out of communication with either of the ports 59 and 60, at which time the exhaust passages 62 and 63 will also be out of communication with their respective exhaust ports 57 and 58.

In order that the pipe conductor 52 may not interfere with the movement of the cylinder, I provide a longitudinal slot 64 in the housing 16 of a width sufficient to clear the conductor 52.

Assuming that the cap 11 with the gasket 15 in place thereon has been pushed into the end of the pipe 10 as far as it will go, that is, until the rim flange on the cap engages the beveled end of the pipe, the tool is then caused to approach the pipe end, or vice versa,

and the parts are guided so as to direct the cap rim into the groove 19, thereby centering the tool upon the pipe and cap. At this time the cylinder 30, 31, 34 will be in the 5 position illustrated in Fig. 1, as will also the links and levers 40 and 44 and the shoes 48. The operator then turns the handle 55 to move valve passage 61 into communication with port 59, and to cause curved passage 63 10 to connect ports 58 and 60. The pressure fluid in the cylinder space to the rear of the piston will then be exhausted through conductor 53, port 60 and exhaust port 58, while fluid will be admitted through flexible conductor 56, passage 61, port 59 and pipe 52 to the cylinder space in front of the piston. The cylinder will thereby be slid forward upon the post 20 from the position of Fig. 1 15 to that of Fig. 2, whereby the shoes 48 will be brought into parallelism with the cap side wall and pressed against the bead 14 to expand the same to the form shown at 14' in Fig. 2 and to flatten the gasket 15 to the form shown at 15' in that figure. The cap is by 20 this means firmly locked in place, and the joint between the cap and the pipe effectively sealed. The handle 55 is then again manipulated to connect the passage 61 with the port 60 and the passage 62 with the ports 57 and 59, 25 whereupon the cylinder travels rearwardly to the position of Fig. 1, retracting the shoes 48. The tool and the pipe may then be separated.

The modification illustrated in Fig. 6 is 30 a hand tool, operating upon principles similar to those of the power tool above described. It comprises a disc 70 of the same general nature as the disc 37 and links and levers 71 and 72 similar to the links and levers 40 and 44, respectively. The carrier plate 73, however, is not secured to the post 74. On the contrary these two parts are relatively rotatable, and 75 is a bearing adapted to take the thrust which occurs during such rotation. At the center of the disc 70 there is 40 fixed a nut 76 which meshes with a coarse thread 77 on the post 74. To the outer extremity of this post there is secured a hand wheel 78 by means of which the post may be 45 turned. Other means might, of course, be substituted, and if it were desired to employ power a pulley or gear might be used. Rotation of post 74 in its bearing in plate 73 obviously causes the disc 70 to travel in- 50 wardly or outwardly, depending upon the direction of rotation of the wheel 78, and in this manner the levers 72 may be operated in the same way as in the case of the preferred form of the invention previously de- 55 scribed.

In the foregoing description I have necessarily gone somewhat into detail in order to explain fully the particular embodiments of the invention herein illustrated, but I desire 60 it to be understood that such detailed disclosure

sures are not to be construed as amounting to limitations, except as they may be included in the appended claims.

Having thus described my invention I claim:

1. In a tool for sealing and securing in place cup shaped caps, a lever carrying plate, means associated therewith for centering the plate with respect to the cap, levers pivotally mounted upon the carrier plate and projecting through openings therein, an arcuate shoe upon the forward end of each lever having a curvature approximating that of the cap side wall, and means for moving simultaneously the rear ends of said levers to force said shoes outwardly. 70

2. In a tool for sealing and securing in place cup shaped caps, a lever carrying plate, means associated therewith for centering the plate with respect to the cap, a series of evenly spaced levers pivotally mounted upon the carrier plate and projecting through openings therein, an arcuate shoe upon the forward end of each lever, said shoes having outer working faces with a curvature approximately the same as that of the cap side wall, the adjacent ends of the shoes approaching each other closely, and means for moving the rear ends of said levers inwardly to force said shoes outwardly against the cap side 80 wall. 85

3. In a tool for sealing and securing in place cup shaped caps, a lever carrying plate, said plate having a circular groove therein on its forward side for centering the plate with respect to the cap, tangentially arranged pivots mounted upon the plate inwardly of said groove, a lever mounted upon each of said pivots projecting rearwardly through an opening in said plate, an arcuate shoe upon the forward end of each lever, said shoe having a curvature approximating that of the cap side wall, and means for moving the rear ends of said levers inwardly to force said shoes outwardly. 100

4. In a tool for sealing and securing in place cup shaped caps, a lever carrying plate having a rearwardly extending centrally positioned post secured thereto, means associated with the plate for centering the same with respect to the cap, levers pivotally mounted upon the carrier plate and projecting through openings therein, a laterally extending expander shoe upon the forward end of each lever, a disc slidable upon said post toward and away from said carrier plate, operative connections between said disc and levers adapted to swing said levers upon their pivots when the disc is moved backward and forward, and means for moving 110 said disc as aforesaid. 115

5. In a tool for sealing and securing in place cup shaped caps, a lever carrying plate having a rearwardly extending centrally positioned post secured thereto, means asso- 120

ciated with the plate for centering the same with respect to the cap, levers pivotally mounted upon the carrier plate and projecting through openings therein, a laterally extending expander shoe upon the forward end of each lever, a disc slidably upon said post toward and away from said carrier plate, a link connecting the rear end of each lever with said disc, said levers and links being respectively uniform in length, and means for moving said disc backward and forward upon said post.

6. In a tool for sealing and securing in place cup shaped caps, a lever carrying plate having a rearwardly extending centrally positioned post secured thereto, means associated with the plate for centering the same with respect to the cap, levers pivotally mounted upon the carrier plate and projecting through openings therein, a laterally extending expander shoe upon the forward end of each lever, a cylinder slidably mounted upon said post, a piston within the cylinder secured to the post, means for admitting pressure fluid to and exhausting it from said cylinder on either side of said piston, and operative connections between said cylinder and levers adapted to swing said levers on said pivots when the cylinder is moved backward and forward.

7. In a tool for sealing and securing in place cup shaped caps, a lever carrying plate having a rearwardly extending centrally positioned post secured thereto, means associated with the plate for centering the same with respect to the cap, levers pivotally mounted upon the carrier plate and projecting through openings therein, a laterally extending expander shoe upon the forward end of each lever, a disc slidably upon said post toward and away from said carrier plate, said carrier plate having attached to its periphery a cylindrical housing within which said disc is adapted to move, operative connections between said disc and levers adapted to swing said levers upon their pivots when the disc is moved backward and forward, and means for moving said disc as aforesaid.

8. In a tool for sealing and securing in place cup shaped caps, a lever carrying plate having a rearwardly extending centrally positioned post rotatably mounted therein, means associated with the plate for centering the same with respect to the cap, levers pivotally mounted upon the carrier plate and projecting through openings therein, a laterally extending expander shoe upon the forward end of each lever, a disc threadably mounted on said post, operative connections between said disc and levers adapted to swing the levers upon their pivots when the disc is moved backward and forward, and a hand-wheel secured to the rear end of said post.

9. An apparatus of the character described,

comprising pivotally mounted jaws provided with levers, a fluid pressure operated member movable toward and away from the jaws, and toggle links pivotally connecting said member to the jaws, said member including a cylinder movable toward and away from said jaws, and means for alternately introducing pressure fluid into the opposite ends of the cylinder.

10. An apparatus of the character described, comprising a head, arms extending through and pivotally connected to the head, a segmental shaped jaw arranged upon each arm forwardly of the head, and means for rocking said arms, said means including a guide bar connected to and extending from the head, a member slidably mounted upon the guide bar, and link means operatively connecting the arms to said member.

11. An apparatus of the character described, comprising a head, arms extending through and pivotally connected to the head, jaws carried by the outer ends of the arms, guide means rigidly connected to the head, a movable member guided by said means, and links operatively connecting the last mentioned member to said arms for causing the jaws to move radially outward when said member moves toward the head.

12. An apparatus of the character described, comprising a head, arms extending through and pivotally connected to the head, jaws carried by the outer ends of the arms, a guide cylinder fixed to the head, a member slidably mounted in the cylinder and movable toward and away from said head, and toggle links pivotally connecting said member to the inner ends of the arms.

13. An apparatus of the character described, comprising a head, arms pivotally connected to and extending through the head, jaws carried by the outer ends of the arms, guide means rigidly connected to the head and extending in the same general direction as the arms, a member slidably mounted on the guide means and movable toward and away from the head, and links pivotally connecting the member to the inner ends of the arms.

14. An apparatus of the character described, comprising a head, arms pivotally connected to the head, jaws carried by the outer ends of the arms, a guide rod rigidly connected to the head and extending in the same general direction as the arms, a piston fixed to said guide rod, a cylinder slidably mounted on the rod and housing the piston, means for introducing pressure fluid into and discharging pressure fluid alternately from opposite ends of the cylinder, and toggle link means connecting the cylinder to the arms.

15. An apparatus of the character described, comprising a head, arms pivotally connected to the head, jaws carried by the

outer ends of the arms, a cylinder fixed to the head, a movable cylinder operable in the first mentioned cylinder, a fixed piston arranged within the movable cylinder, means for introducing pressure fluid into and discharging said fluid from opposite ends of the movable cylinder, and means pivotally connecting the movable cylinder to said arms.

16. A pipe sealer expanding tool comprising a stationary head, arms extending through the head and having portions near their outer ends pivotally connected to the latter, a jaw arranged upon each arm forwardly of the head, a guide bar rigidly connected to and extending rearwardly from the head, a member slidably mounted upon the guide bar, and links having their inner ends connected to the arms and their outer ends connected to said member, whereby when the member moves toward the head, the jaws will be moved radially outward.

17. A pipe sealer expanding tool comprising a head, arms pivotally connected to the head, jaws arranged upon the arms forwardly of the head, a guide bar connected to and extending from the head, a member slidably mounted upon the guide bar, links having their inner ends pivotally connected to said arms and their outer ends pivotally connected to said member, and means for preventing each link from moving outwardly beyond a straight line which extends from the point where the arm is pivoted to the head to the point where its respective link is pivoted to said member.

18. A pipe sealer expanding tool comprising a head, arms pivotally connected to the head, jaws arranged upon the arms forwardly of the head, inner and outer guide members rigidly connected to the head and extending rearwardly therefrom, a member slidably mounted between and guided by said members, links having their inner ends pivotally connected to the arms and their outer ends pivotally connected to said slid-
able member, and means for preventing each link from moving radially outward beyond a straight line which extends from the point where the arm is pivoted to the head to the point where its respective link is pivoted to said slid-
able member.

In testimony whereof, I hereunto affix my signature.

WAYNE B. THOMAS.
